UNITED STATES PATENT OFFICE.

HENRY BERRY, OF HUNTINGTON, ASSIGNOR TO THE DERBY SILVER COMPANY, OF BIRMINGHAM, CONNECTICUT.

DESIGN FOR A CARD-RECEIVER.

SPECIFICATION forming part of Design No. 17,163, dated March 8, 1887.

Application filed December 8, 1886. Serial No. 221,020. Term of patent 3½ years.

To all whom it may concern:

Be it known that I, HENRY BERRY, a citizen of the United States, residing at Huntington, in the county of Fairfield and State of Connecticut, have invented and produced a new and original Design for Card-Receivevers; and I do declare the following to be a full, clear, and exact description of the same, reference being had to the accompanying drawings, forming a part thereof.

Figure 1 of the drawings is a side view of my newly-designed card-receiver, and Fig. 2 is a plan view of the same.

My design consists in the representation of a spray of a strawberry-vine with flowers and fruit, and the representation of a cent.

My design also consists in ornamenting the handle with sprays of marguerites or other flowers.

B indicates the receiving-plate, having a scalloped periphery or outline, and is mounted on a suitable base. A indicates the handle, which extends from the base to a point above

the receiving-plate. The handle is ornamented with sprays of marguerites, which, after passing from the base to the top of the handle, branch laterally in opposite directions, so as to connect the upper portion of the said handle with the plate. On the top of the plate is represented a spray of a strawberry-vine bearing flowers and fruit. The face of this plate has a cent represented in a raised manner.

I claim—

The design for a card-receiver herein shown and described, the same consisting of marguerites ornamenting the handle, a spray of strawberries on the face of the receiving-plate, and a representation of a penny on the said plate.

In testimony whereof I affix my signature in presence of two witnesses.

HENRY BERRY.
